(Cl. D52—1)

To all whom it may concern:

Be it known that I, Clarence A. Vanderbrook, a citizen of the United States, residing at Newark, in the county of Wayne and State of New York, have invented a new, original, and ornamental Design for a Landscape Planning Rule, of which the following is a specification, reference being had to the accompanying drawing, forming a part thereof in which:

Fig. 1 is a plan view of a landscape planning rule, showing my new design; and

Fig. 2 is an edge view thereof.

I claim:

The ornamental design for a landscape planning rule, as shown.

CLARENCE A. VANDERBROOK.
